(57) **CLAIM**

The ornamental design for a confectionary mold, as shown
and described.

DESCRIPTION

FIG. 1 is a top perspective view of a confectionary mold
showing our design;

FIG. 2 is a bottom perspective view thereof;

FIG. 3 is a top view thereof;

FIG. 4 is a bottom view thereof;

FIG. 5 is a first side view thereof;

FIG. 6 is a second side view thereof;

FIG. 7 is a first end view thereof; and,

FIG. 8 is a second end view thereof.

The long-and-short broken lines form an unclaimed bound-
ary around at least a portion of the claimed subject matter,
and form no part of the claim. The even-length broken lines
show the remainder of the article, are directed to environ-
ment, represent unclaimed subject matter, and form no part
of the claimed design.
